UNITED STATES PATENT OFFICE.

CHRISTIAN SMITH, OF DETROIT, MICHIGAN.

BRUSH.

1,363,282.

Specification of Letters Patent. Patented Dec. 28, 1920.

Application filed April 4, 1918. Serial No. 226,559.

To all whom it may concern:

Be it known that I, CHRISTIAN SMITH, a citizen of the United States, residing at Detroit, county of Wayne, State of Michigan, 5 have invented a certain new and useful Improvement in Brushes, and declare the following to be a full, clear, and exact description of the same, such as will enable others skilled in the art to which it pertains to 10 make and use the same, reference being had to the accompanying drawings, which form a part of this specification.

This invention relates to brushes and brush blocks therefor, and a primary object 15 of the invention is to provide a brush in which the bristles are permanently maintained in such angular or flared relation with the block to enable the brush to be used in corners of a room, or of an article being 20 cleaned as a counter or display case, without liability of striking the block against portions of the structure being cleaned. A further object of the invention is to provide a brush block permitting the use of short bristles 25 and lessening the cost of the brush without detriment to the efficiency thereof, and further providing a brush in which the majority of bristles are practically half the length of the marginal row of bristles giving 30 the brush the appearance of a full-bristled brush. A further object is to provide a brush in which the longer row of marginal bristles are supported at an angle to a vertical plane partly by the block and partly by 35 the short bristles tending to prevent curling of the long bristles beneath the block resulting in a brush serviceable for a longer period of time than is usual with brushes of ordinary construction. These several objects 40 and novel features of the invention are hereinafter more fully described and claimed and shown in the accompanying drawings in which—

Figure 1 is a front elevation of a brush 45 and brush block embodying my invention.

Fig. 2 is a cross section taken on line $\pi-\pi$ of Fig. 1.

It is to be understood that the brush block 50 may be made for various brushes, for instance a floor brush, window brush, counter brush or any other type of brush that may be desired, and that the general design and form of the block will vary depending upon the type of brush to be made. All of the 55 blocks and brushes, however, of any type may readily embody the invention herein disclosed and which is illustrated principally in Fig. 2 in which the block 1 practically midway between the upper and lower horizontal faces is provided with a shoulder 60 2 upwardly inclined at an angle to the horizontal. This shoulder extends completely around the block 1 as will be understood from Fig. 1 and a marginal row of apertures or recesses 3 drilled therein at practically a 65 right angle to the face of the shoulder and comparatively long bristles 4 are inserted and secured therein in the usual manner in which bristles are fixed in position in the blocks. Instead of the apertures 3 as shown 70 the shoulder 2 may be otherwise adapted to maintain the bristles in position and any mode of fastening may be employed as may be desired. In any event the bristles extend downwardly from the shoulder at an angle 75 so that the bristles are flared outwardly from the block whereby the terminal ends of the marginal row of bristles form an outline greater in perimeter than the outline of the block whether oblong or rectangular as 80 shown or other form. The block is also provided with what I have termed an extension 5 beneath the peripheral shoulder 2 and having a face on each side occupying a plane at the same angle to the horizontal as the 85 axis of the apertures 3 or the longitudinal axis of the bristles supported by the shoulder. The angular face of the extension 5 provides a support for the marginal row of bristles tending to prevent the same from 90 turning beneath the block as is usual in brushes not provided with such an extension.

Heretofore brush blocks have been drilled or provided with channels or the like so positioned that the bristles normally set at an angle to the block but in use such bristles become permanently bent out of original position which is detrimental to the usefulness of the device, but by providing a block having a portion extending below the point of attachment of the marginal bristles, these bristles lie against the angular face of the extension which prevents the bristles from being turned permanently beneath the block 100 whereby the usefulness and life of the brush is enhanced and a block is provided in which the bristles prevent the block from being readily brought into forcible contact with parts of the article being cleaned. It is 105 further to be noted that the sides of the extension are formed at such an angle that, in

cross section as shown in Fig. 2, the width of the lower face of the extension combined with the thickness of the two tufts on opposite sides is greater than the width of the block proper in which the marginal bristles are mounted. The usefulness of such construction is illustrated in Fig. 2, in which a dotted line 50 indicates a corner of an article, as for instance a china cabinet, and from which it will be noted that the block proper may not be readily brought forcibly in contact with the cabinet as the bristles maintained in position by the extension would first contact the article and prevent the head of the block from striking the same. This feature of course is serviceable in the cleaning of any device as for instance the corner of the floor when it is not desired to strike the base board. The bristles by the construction shown would be maintained to position at such an angle that the corners could be thoroughly cleaned and the block not come in contact therewith.

It is further to be noted that the block is formed with the bristles extending entirely about the block, both sides and ends being provided with the marginal angularly positioned bristles as is illustrated. The lower horizontal face of the block is also provided preferably with a series of apertures 10, the marginal rows of which are positioned at an angle and the rows are gradually changed in angle to nearly vertical at the center so that the entire lower face of the extension is covered with tufts which are comparatively short in length resulting in a saving of stock and providing a more serviceable brush in that these center rows of bristles are perceptibly stiffer in action to give the desired cleaning effect and the marginal bristles of the said lower face being at an angle support the free ends of the long bristles supported from the shoulder 2 of the block and prevent the lower ends thereof from being permanently curled beneath the block.

From the above it will be readily understood that a brush is provided that is of great utility in that the brush may be used without liability of striking the article to be cleaned and that a more thorough cleaning may be had by reason of the stiffer bristles carried by the extension as described, and that an article considerably cheaper and of longer life than the usual brush is provided.

Having thus fully described my invention what I claim is—

1. In a brush, a block provided with an upwardly inclined peripheral shoulder between the upper and lower horizontal faces thereof, the sides of the block below the shoulder being formed substantially at a right angle to the said shoulder, and a marginal row of comparatively long bristles

supported in apertures provided in the shoulder to lie against the said angularly disposed sides of the block.

2. A brush comprising a block having an upwardly inclined shoulder formed intermediate the upper and lower faces thereof and the side portions below the shoulder having a face extending outwardly from the point of meeting the shoulder at an angle to a vertical plane, the width across the lower face of the block being substantially equal to the greatest width thereof, the upwardly inclined face of the shoulder being adapted to support a marginal row of comparatively long bristles contacting the adjacent angular face of the lower portion of the block, and a plurality of rows of short bristles terminating in the same plane as the longer bristles supported in the lower face of the block and flared to support the free ends of the long bristles.

3. A brush block having a peripheral shoulder intermediate its upper and lower face positioned at an angle to a horizontal plane, the face of the portion of the block below the shoulder being formed at substantially a right angle to the face of the shoulder, the shoulder being drilled at a right angle to the face thereof, a series of comparatively long bristle tufts in the recesses provided therefor and a plurality of rows of short length bristles inserted in the lower face of the block, the outer row of short bristles being positioned at an angle to a vertical plane to support the said longer bristles and the inner rows gradually changing in angle to practically vertical position at the center of the block.

4. A brush block having a peripheral substantially right-angled recess formed in the sides thereof, the walls of the recess being at an angle to a horizontal and vertical plane respectively, a marginal row of bristles carried in the shoulder formed by the notch and lying against the other wall thereof and a plurality of intermediate rows of bristles, the outer row of which is positioned at an angle to the vertical plane to provide a support for the marginal row, the intermediate rows gradually altering forming an angle to a vertical plane to occupy a vertical position at the center.

5. In a brush, a block provided with an upwardly inclined peripheral shoulder between the upper and lower horizontal faces thereof, the sides of the block below the shoulder being formed substantially at a right angle to the said shoulder, a marginal row of comparatively long bristles supported in apertures provided in the shoulder and contacting the said angular disposed sides of the block, and a series of rows of short bristles carried in the lower horizontal face of the block, the outer marginal row of short bristles being flared to support the lower

ends of the long bristles and succeeding rows of short bristles gradually altering in angle to occupy a vertical plane at the center.

6. In a brush, a block provided with an upwardly inclined peripheral shoulder between the upper and lower horizontal faces thereof, the sides of the block below the shoulder being formed substantially at a right angle to the shoulder, said shoulder having a series of recesses formed therein, each having its longitudinal axis parallel to

the plane of the said sides, the lower horizontal face of the block having tuft recesses formed therein in substantially parallel rows, the longitudinal axes of said recesses of the several rows from the inner to the outer row transversely of the block gradually changing in position from a vertical plane to an angle to the vertical. 15

In testimony whereof I sign this specification. 20

CHRISTIAN SMITH.
